UNITED STATES PATENT OFFICE

164,861

WHISTLE OR SIMILAR ARTICLE

Karl U. Ingard, Newton Center, Mass., assignor to
Manning, Maxwell & Moore, Incorporated, New
York, N. Y., a corporation of New Jersey

Application April 4, 1951, Serial No. 14,709

Term of patent 14 years

(Cl. D72—1)

To all whom it may concern:

Be it known that I, Karl U. Ingard, a subject of Sweden, residing in Newton Center, county of Middlesex, and Commonwealth of Massachusetts, have invented a new, original, and ornamental Design for a Whistle or Similar Article, of which the following is a specification, reference being had to the accompanying drawings, forming a part thereof, wherein

Fig. 1 is a front perspective view of a whistle, showing my new design; and

Fig. 2 is a rear perspective view thereof.

I claim:

The ornamental design for a whistle or similar article, substantially as shown.

KARL U. INGARD.
